(57) **CLAIM**

The ornamental design for a carton, as shown and described.

DESCRIPTION

FIG. 1 is a front perspective view from the top, showing the front side and the right side of a carton in accordance with one embodiment our new design;

FIG. 2 is a front elevational view of said carton;

FIG. 3 is a rear elevational view of said carton;

FIG. 4 is a left side elevational view of said carton;

FIG. 5 is a right side elevational view of said carton;

FIG. 6 is a top plan view of said carton;

FIG. 7 is a bottom plan view of said carton; and

FIG. 8 is a front perspective view from top, showing the left side and the front side of the carton in accordance with said one embodiment our new design;

FIG. 9 is a front perspective view from the top, showing the front side and the right side of a carton in accordance with a second embodiment our new design;

FIG. 10 is a front elevational view of said carton;

FIG. 11 is a rear elevational view of said carton;

FIG. 12 is a left side elevational view of said carton;

FIG. 13 is a right side elevational view of said carton;

FIG. 14 is a top plan view of said carton;

FIG. 15 is a bottom plan view of said carton; and

FIG. 16 is a front perspective view from top, showing the left side and the front side of the carton in accordance with said second embodiment our new design;

FIG. 17 is a front perspective view from the top, showing the front side and the right side of a carton in accordance with a third embodiment our new design;

FIG. 18 is a front elevational view of said carton;

FIG. 19 is a rear elevational view of said carton;

FIG. 20 is a left side elevational view of said carton;

FIG. 21 is a right side elevational view of said carton;

FIG. 22 is a top plan view of said carton;

FIG. 23 is a bottom plan view of said carton; and,

FIG. 24 is a front perspective view from top, showing the left side and the front side of the carton in accordance with said third embodiment our new design.

(Continued)

In the drawings, the broken line showing portions of a carton depicts environment and forms no part of the claim.
